(57) **CLAIM**

The ornamental design for a rack organizer for cables, as shown and described.

DESCRIPTION

FIG. 1 is a perspective view of a rack organizer for cables; FIG. 2 is an enlarged detail view taken along line 2-2 of FIG. 1.

FIG. 3 is a right side elevational view of a rack organizer for cables. The left side elevational view is a mirror image thereof.

FIG. 4 is a top plan view of a rack organizer for cables; FIG. 5 is a front view thereof;

FIG. 6 is a rear view thereof;

FIG. 7 is a bottom view thereof; and,

FIG. 8 is a perspective view thereof, shown in environmental use.

The broken lines shown represent unclaimed subject matter and form no part of the claimed design.
